UNITED STATES PATENT OFFICE.

LOUIS ERNEST FRANCOIS FERRETTE, OF PARIS, FRANCE.

AIR PUMP FOR SAFETY LAMPS.

Application filed November 21, 1923. Serial No. 676,154.

To all whom it may concern:

Be it known that I, LOUIS ERNEST FRANCOIS FERRETTE, engineer, citizen of the French Republic, residing at Paris, 41 Rue 5 Vital (Seine), France, have invented certain new and useful Improvements in Air Pumps for Safety Lamps, of which the following is a specification.

This invention has reference to miners' 10 incandescent safety lamps of the kind in which benzine, petrol, or mineral oil is used as the liquid illuminant.

According to the present invention, a miner's safety lamp of this kind is provided 15 with a pump for supplying to a reservoir containing the illuminant the air necessary for the circulation of the illuminant to a burner, said pump having means whereby the air pressure within the reservoir is automatically relieved when a predetermined 20 pressure is reached.

Preferably, the pump comprises an outer casing or barrel within which a piston provided with a hollow piston rod, through 25 which air is induced into said casing or barrel, is slidably arranged, and within which casing delivery and safety valves are also arranged. Said valves may be normally held closed by spring pressure, the delivery 30 valve being opened by the hollow piston rod on the instroke of the latter and the safety valve opened only when the air pressure within the reservoir becomes excessive. When the piston is drawn outwardly, air is 35 induced into the piston barrel, through the hollow piston rod, and passes through the delivery valve out of the pump barrel, preferably, into an outer tube enclosing the pump, whence it passes into the lamp reservoir. When the air pressure within the latter becomes excessive, some of the air re- 40 enters the outer tube and, after forcing the safety valve open, passes through a by-pass into the piston barrel and thence through 45 the hollow piston rod to the atmosphere.

Reference will now be made to the annexed drawing which illustrates, by way of example, a vertical sectional view of a constructional form of the present invention.

As shown, the air pump 43 is secured 50 within an outer protecting tube 63, and is adapted to apply pressure to the liquid illuminant contained in the reservoir 1 of the lamp. The said pump comprises a cylindrical body, 44, in which operates a piston 51 having a cup shaped leather packing 55

and a rod 46 provided at its outer end with a button 47. The rod 46 is secured to the piston by means of a threaded washer 52. A stuffing box 50 is arranged in the pump 60 body 44 and is provided with a recess which is arranged to accommodate a shoulder on the button 47. The pump is also provided with a delivery valve 49 having a tail piece 60 and held in its seat 56 by means of a 65 spring 53. An air hole 54 is formed in the pump body 44 between a partition 55 secured in the pump body and the valve seat 56. The partition 55 is arranged between the delivery valve 49 and a safety valve 58 70 held in its seat 57 by means of a spring 59 and adapted to open only when the pressure in the reservoir 1 becomes excessive. A by-pass tube 61 is arranged in the pump body 44 and provides communication between the chamber of the pump containing the safety valve and the piston barrel, while a port 62, communicating with the reservoir 1, is provided in the tube 63. A liner 64, secured in the tube, maintains the pump 43 80 in position therein.

When the piston 51 is pulled outwardly, air is drawn into the hollow rod 46 at the mouth 65 thereof. When the end of the stroke is reached, the operator closes the hollow rod 46 by placing his thumb on the button 47 over the hole therein, so that during the inward stroke of the piston the air is compressed in the pump barrel until the washer 52 of the rod 46 comes into contact 90 with the tail piece 60 of the delivery valve 49, opening the latter and permitting the compressed air to pass into the chamber between the partition 55 and the valve seat 56.

The washer 52 is arranged to contact with 95 the tail piece 60 when the shoulder or rib on the button 47 engages in the recess in the stuffing box 50. The compressed air passes through the hole 54 into the tube 63, whence it passes, through the hole 62, into 100 the reservoir 1 of the lamp above the liquid illuminant. During the compression of the air, on the instroke of the piston 51, a certain amount of air which passes through the by-pass tube 61 into the safety valve chamber, is returned therefrom when the delivery valve 49 is opened, and passes through the latter. The course of the air is clearly indicated by the full line arrows shown on the drawing.

As previously stated, the safety valve 58 is only opened when the pressure of the air

within the reservoir 1 becomes excessive. In this case, the air re-enters the tube 63 through the port 62 and, following the course of the arrows shown in chain lines, 5 forces open the safety valve 58, and passes through the by-pass tube 61 into the pump barrel, from whence it escapes through the hollow piston rod 46 into the atmosphere.

Having now particularly described and 10 ascertained the nature of my said invention and in what manner the same is to be performed, I declare that what I claim is:

1. In a lamp, the combination, with a liquid fuel reservoir, of an air pump for 15 placing the fuel under pressure; said pump comprising a pump casing within the reservoir having an inlet and an outlet for air, a hand-operated piston in the pump casing, a normally-closed delivery valve in said 20 casing adapted to be opened during the in-stroke of the piston for admitting to the air outlet the air forced ahead of the piston, and a normally-closed safety valve in said pump casing adapted to open automatically 25 when the pressure in the reservoir becomes excessive.

2. In a lamp, the combination, with a liquid fuel reservoir, of an air pump for 30 placing the fuel under pressure; said pump comprising a pump casing within the reservoir having an inlet and an outlet for air, the air outlet being located intermediate the ends of said casing, a hand-operated piston in the pump casing, a normally-closed delivery valve in said casing located in advance 35 of the air outlet and adapted to be opened during the in-stroke of the piston so as to admit to said outlet the air forced ahead of the piston, and a normally-closed safety 40 valve mounted in an opening in the inner end of the pump casing and adapted to open automatically when the pressure in the reservoir becomes excessive.

3. In a lamp, the combination, with a liquid fuel reservoir, of an air pump for 45 placing the fuel under pressure; said pump comprising a casing having an air port, a piston in the casing having a tubular operating rod for the passage of air there-

through, a delivery valve in said casing under the control of the piston, a closed chamber in the rear portion of the casing, a normally-closed safety valve in said chamber adapted to open automatically when the pressure in the reservoir becomes excessive, 55 and means for conducting the air admitted to said chamber when the safety valve opens to a point where it can escape through the bore of the piston rod.

4. In a lamp, the combination, with a liquid fuel reservoir, of an air pump for 60 placing the fuel under pressure; said pump comprising a casing, a hand-operated piston having a tubular rod for the passage of air therethrough, a normally-closed delivery 65 valve in the casing adapted to be opened by the operation of the piston, a normally-closed safety valve in said casing adapted to open automatically when the pressure in the reservoir becomes excessive, and means 70 for conducting the air admitted into the casing when the safety valve opens to a point where it can escape through the bore of the piston rod.

5. In a lamp, the combination, with a liquid fuel reservoir, of an air pump for 75 placing the fuel under pressure; said pump comprising a casing, a partition therein, inner and outer valve seats in the casing at 80 opposite sides of the partition and spaced therefrom, a normally-closed delivery valve in the inner seat, a piston in said casing to open the delivery valve, means for admitting air into the casing during the movement of the piston in one direction, said 85 casing having an air port through which the air is discharged when the piston moves in the other direction, a normally-closed safety valve in the outer seat adapted to 90 open automatically when the pressure in the reservoir becomes excessive to admit air into the space between said outer seat and the partition, and an air passage for conducting the air from said space to a point in front 95 of the piston to escape therefrom through said air-admitting means.

In testimony whereof I affix my signature.

LOUIS ERNEST FRANÇOIS FERRETTE.
